(57) **CLAIM**

The ornamental design for a replacement tail lens assembly
for pick-up trucks, as shown and described.

DESCRIPTION

FIG. 1 is a right side perspective view of the replacement tail
lens assembly of the present design;

FIG. 2 is a right side perspective view of the replacement tail
lens assembly of the present design showing the cover of the
replacement tail lens removed;

FIG. 3 is a right side view of the replacement tail lens
assembly of the present design;

FIG. 4 is a front view of the replacement tail lens assembly
of the present design;

FIG. 5 is a top sectional view of the replacement tail lens
assembly of the present design; and,

FIG. 6 is a right side perspective view of the replacement tail
lens assembly of the present design showing the lens assem-
bly installed on a pick-up truck.

The broken lines showing of the lens assembly in FIG. 5 and
of the pick-up truck in FIG. 6 are for illustrative purposes
only and form no part of the claimed design.
